[57] **CLAIM**

The ornamental design for the vehicle interior lamp assembly adapted for use with recreational vehicles, outfitted vans, shuttlebuses and the like, as shown and described.

DESCRIPTION

FIG. 1 is a front, top and left end perspective view of a vehicle interior lamp assembly adapted for use with recreational vehicles, outfitted vans, shuttlebuses and the like, according to the invention;

FIG. 2 is a top plan view of FIG. 1;

FIG. 3 is a front elevation of FIG. 1, the rear elevational view being a mirror image of the view in FIG. 3;

FIG. 4 is a left end elevation of FIG. 1, the right end elevation being a mirror image of the view in FIG. 4;

FIG. 5 is a bottom plan view of FIG. 1;

FIG. 6 is a front, top and left end perspective view of an alternative embodiment of a vehicle interior lamp assembly adapted for use with recreational vehicles, outfitted vans, shuttlebuses and the like, according to the invention;

FIG. 7 is a top plan view of FIG. 6;

FIG. 8 is a front elevation of FIG. 6, the rear elevational view being a mirror image of the view of FIG. 8;

FIG. 9 is a right end elevation of FIG. 6;

FIG. 10 is left end elevation of FIG. 6; and,

FIG. 11 is bottom plan view of FIG. 6.

The broken lines are shown for illustrative purposes only and form no part of the claimed design.
